MERCHANDISE ENVELOPE

Morton Bookler, Merion, Pa.

Application March 1, 1952, Serial No. 18,749

Term of patent 14 years

(Cl. D58—2)

To all whom it may concern:

Be it known that I, Morton Bookler, a citizen of the United States and a resident of Merion, county of Montgomery, State of Pennsylvania, have invented a new, original, and ornamental Design for Merchandise Envelope, of which the following is a specification, reference being had to the accompanying drawings, forming a part hereof, wherein—

I claim:

The ornamental design for a merchandise envelope, as shown.

MORTON BOOKLER.
